UNITED STATES PATENT OFFICE.

JOSEPH W. JONES, OF NEW YORK, N. Y.

REFRIGERATING APPARATUS.

Application filed August 12, 1926. Serial No. 128,893.

This invention relates to refrigerating apparatus, an object of the invention being to provide an improved construction of pump, in combination with high pressure and low pressure coils, which produces an apparatus where leakage is prevented and where highly efficient results are had.

With apparatus such as heretofore known the leakage of gas occurred. This is not only 10 objectionable but causes many apparatus to be discarded after installation, and so far as I have any knowledge no effectual remedy has been provided for this serious defect prior to my invention.

15 It is therefore the primary object of my invention to provide an apparatus where leakage is practically impossible and which by reason of an improved construction and arrangement of parts an economical and 20 highly efficient apparatus is produced.

With these and other objects in view, the invention consists in certain novel features of construction and combinations and arrangements of parts, which will be more 25 fully hereinafter described and pointed out in the claims.

In the accompanying drawings—

Figure 1 is a view in elevation, more or less diagrammatically illustrating my complete apparatus;

Figure 2 is a view in vertical section through my improved pump and its support;

Figure 3 is a view in vertical section on the staggered line 3—3 of Figure 2;

Figure 4 is a top plan view of the pump. I shall first describe the construction of my improved apparatus with particular reference to the pump and shall then set forth the operation.

Referring more particularly to Figure 1, A represents a bed on which my improved pump B is rigidly secured. C, C are high pressure coils and D a low pressure coil connected by a pipe E with the high pressure coils, and having a pressure reducing valve F in said pipe E. G represents a motor which is operatively connected by a belt or other suitable mechanism with a combination flywheel and fan J, on the drive shaft K of the pump, so that this member J functions to cool the pump and the high pressure coils.

I, of course, do not limit myself to the precise arrangement of the parts illustrated and above described as this is capable of a wide range of modification, but I have il-

lustrated what I believe to be a preferred form.

Referring more particularly to Figures 2, 3 and 4, of the drawings, it will be noted that the cylinder 1 of the pump B is open at its lower end where it is secured upon a base 2 with a packing gasket 3 interposed between the pump and the base to insure a tight joint.

4 represents a piston which is mounted to reciprocate in the cylinder 1 and has a rod 5 fixedly secured to the center thereof and also fixedly secured to a vertically reciprocating block 6 mounted in a guide 7 on the base 2. This block 6 has a slot 8 therein in which a laterally reciprocating block 9 is mounted, and an eccentric 10 on shaft K turns in the block 9 to impart the desired stroke to the piston. This stroke is relatively short and is positive in both directions.

The lower portion of the base 2 constitutes a chamber 11 for lubricant 12, the walls of the guide 9 being perforated as shown at 13 and 14 to permit the lubricant 80 to splash and thoroughly lubricate the movable parts of the piston drive. The upper wall of the chamber 12 is preferably provided with wick filled openings 15 which prevent undue splashing and allow the 85 chamber to be supplied with lubricant when occasion may require.

A disc 16 is rigidly secured on the lower portion of the rod 5 and a flexible corrugated tubular metal wall has its lower end secured 90 to said disc, whereby said lower end is closed, and its upper open end secured to the lower open end of the cylinder 1. The mean diameter of the flexible wall 17 (which as experts in the art will understand is approximately 95 the effective diameter thereof) is practically the same as the internal diameter of the cylinder 1 or the external diameter of the piston 4.

18 indicates a head which is fixed to the upper end of the cylinder 1, and this head is formed with inlet and exhaust valve chambers 19 and 20, respectively. Spring pressed check valves 21 and 22 control communication between the chambers 19 and 20 and the cylinder 1, and these valves are of relatively large diameter so that when opened a relatively large passage is provided for quick movement of the gas, the stroke of the piston being short, such large diameter valves are desirable.

On the head 18 inlet and exhaust valve

casings 23 and 24 are fixed. These valve casings at their lower ends are in open communication with the chambers 19 and 20, and at their upper ends are normally closed by 5 removable plugs 25 and 26, respectively.

The gas from the expansion coil D is returned to the valve casing 23 through the medium of a pipe 26', and a needle valve 27 located in the casing 23 controls a port 28 10 communicating with pipe 26. A second needle valve 29 located in the casing 24 controls a port 30 communicating with a pipe 31 which connects said port with the high pressure coils C, C.

15 32 represents a by-pass pipe which communicates at its lower end with the interior of the cylinder 1, at a point which will not be covered by the down stroke of the piston, and with a port 33 in valve casing 20 23. This by-pass pipe 32 is provided with a check valve 34, allowing the flow of gas upwardly thereof but preventing any movement of the gas in the opposite direction, and a cut-off valve 35 is located in the pipe 25 32 above the check valve 34 for a purpose which will hereinafter appear.

The flexible corrugated tubular metal wall 17 is filled to the desired level with oil 36, and I preferably employ castor oil which 30 I find to be efficient for the purpose. This oil acts as a seal for the piston and the flexible wall does away with the ordinary packing so that there is no movement whatever of the piston rod through any bearing which 35 would be liable to leak. Furthermore, the flexible wall, piston and the cylinder 1 form a chamber 37 which is sealed against leakage as the flexible wall is fixedly secured to the cylinder and expands and contracts with 40 the movement of the piston. Furthermore, the mean diameter of the flexible wall (which, as is well understood by those skilled in the art, is approximately the effective diameter thereof), is practically the 45 same as the diameter of the piston so that in the movement of the several parts there is no variation in the size of the chamber 37. The only point where gas may probably leak is around the packing of the piston 4 and such gas will pass into the chamber 37 and be returned to the system as will now be explained.

The operation of my improved apparatus is as follows:

50 After installation it is of course necessary to remove the air in the system, and to accomplish this I close the port 30 through the medium of the needle valve 29 and remove the plug 26. The pump is then operated to cause the piston 4 to reciprocate and this movement of the piston induces a suction throughout the entire apparatus to draw the air past the valve 29 and force the same past the valve 22 to the atmosphere. 55 This pumping operation is continued un-

til the air is removed, and then the plug 26 is returned to its former position and the needle valve 29 opened. During this initial operation of the pump there is a possibility that portions of the oil 36 may be drawn 70 through the pipe 32 and the cut-off valve 35 is provided to reduce the passage through the pipe 32 or entirely close the same as may be found desirable. Normally, however, this valve 35 is wide open. After 75 the air is exhausted from the apparatus, a gas supply pipe is coupled to the opening closed by the plug 25 and gas is drawn into the apparatus. This plug is then returned to position and the mechanism is ready for 80 use.

In normal operation the piston is reciprocated, drawing the gas from the expansion coil D, through pipe 26', and discharging it under pressure into the high pressure coils 85 C. If during such operation any gas may escape past the piston 4 into chamber 37 it will be immediately returned to the coils by reason of the fact that the downward movement of the piston 4 will induce a suction 90 through the pipe 32 and thus return this surplus gas to the system.

Referring to the operation of the apparatus in terms of pressure, it is desirable that the expansion coil have a pressure of approximately one to three pounds, while the pressure in the coils C is approximately seventy pounds. The pressure within the chamber 37 is maintained at approximately two and a half pounds by the check valve 100 34. Any excessive pressure will cause the check valve to open and the pressure to be automatically reduced.

While I have illustrated and described in detail the specific construction shown in the drawings, it is to be understood that I do not limit myself to such details but consider myself at liberty to make such changes and alterations as fairly fall within the spirit and scope of the appended claims.

I claim:

1. In a refrigerating apparatus, a pump comprising a cylinder open at one end, a piston in said cylinder, a piston rod extending from the piston through the cylinder, a disc fixed on the rod beyond the open end of said cylinder, and a flexible, corrugated, tubular, metal wall connecting said disc and the open end of said cylinder, the end of said flexible wall opposite said disc being 115 also open, whereby said cylinder, flexible wall, piston, and disc form a chamber surrounding said rod.

2. In a refrigerating apparatus, a pump comprising a cylinder open at one end, a piston in said cylinder, a rod connected to the piston and extending through the cylinder, a disc fixed to said rod beyond the open end of the cylinder, a flexible, corrugated, tubular, metal wall connected at one end 130

to the disc and at the other end to the open end of the cylinder, said flexible wall being open where it joins said cylinder, whereby a chamber is formed by said cylinder, flexible wall, disc, and piston, and a by-pass pipe connecting said chamber with the working end of said cylinder.

3. In a refrigerating apparatus, a pump comprising a cylinder open at one end, a piston in said cylinder, a rod connected to said piston and extending through said cylinder, a disc fixed to said rod beyond the open end of the cylinder, a flexible, corrugated, metal, tubular wall connecting said disc with the open end of said cylinder, the end of said flexible wall where it joins said cylinder being open, whereby a chamber is formed by said cylinder, flexible wall, disc, and piston, a by-pass pipe connecting said chamber with the working end of said cylinder, and a check valve in said pipe.

4. In a refrigerating apparatus, a pump comprising a cylinder open at one end, a piston in said cylinder, a rod extending through the cylinder beyond the open end thereof, a disc fixed on said rod beyond the open end of the cylinder, an oil containing, flexible, tubular, corrugated, metal wall connecting said disc with the open end of said cylinder, the end of said flexible wall where it joins said cylinder being open, whereby a chamber is formed by said cylinder, flexible wall, piston, and disc, and a by-pass pipe connecting said chamber with the working end of said cylinder.

5. In a refrigerating apparatus, a pump comprising a cylinder having an open end, a piston in said cylinder, a rod fixed to said piston and extending beyond the open end of said cylinder, a disc on said rod, an oil containing flexible, corrugated, tubular, metal wall connecting said disc with the open end of said cylinder, said flexible wall being open where it joins said cylinder, whereby a chamber is formed by the cylinder, flexible wall, piston, and disc, a by-pass pipe connecting said chamber with the working end of the cylinder, and a check valve in said pipe.

50 6. In a refrigerating apparatus, a pump comprising a cylinder open at its lower end, a piston in said cylinder, a rod connected with said piston and extending out through the open end of said cylinder, a disc fixed on said rod, and a flexible, corrugated, tubular, metal wall of approximately the same mean diameter as the cylinder connected at one end to said disc and at the other end with the open end of said cylinder, said flex-

ible wall being open at the end where it joins said cylinder.

7. In a refrigerating apparatus, a pump comprising a cylinder open at one end, a piston in said cylinder, a rod connected with said piston and extending out beyond the open end of the cylinder, a disc on said rod beyond the open end of the cylinder, a flexible, corrugated, tubular, metal wall of approximately the same mean diameter as said cylinder connected at one end to said disc and at its other open end to the open end of the cylinder, whereby a chamber is formed by said cylinder, flexible wall, piston, and disc, and a by-pass pipe connecting said chamber with the working end of the cylinder.

8. In a refrigerating apparatus, a pump comprising a cylinder open at one end, a piston in said cylinder, a rod connected to said piston and extending out beyond the open end of the cylinder, a disc fixed on said rod beyond the open end of the cylinder, a flexible, corrugated, tubular, metal wall whose mean diameter is approximately that of said cylinder, said flexible wall being connected at one end to said disc and at its other open end to the open end of said cylinder, whereby a chamber is formed by said cylinder, flexible wall, piston, and disc, a by-pass pipe connecting said chamber with the working end of the cylinder, and a check valve in said pipe.

9. As a new article of manufacture, a pump including a vertical cylinder open at its lower end, a piston reciprocating therein, a piston rod connected to said piston and extending out through the open end of said cylinder, a disc fixed on said rod, a flexible, corrugated, tubular, metal wall connecting said disc with the open end of said cylinder, said flexible wall being open where it is connected to said cylinder, said cylinder having an outlet at a point below the stroke of the piston.

10. As a new article of manufacture, a pump including a vertical cylinder open at one end, a piston reciprocating therein, a piston rod connected to said piston and extending out through the open end of said cylinder, a disc fixed on said rod, a flexible, corrugated, tubular, metal wall connecting said disc with the open end of said cylinder, said flexible wall being open where it is connected to said cylinder, said cylinder having an outlet at a point below the stroke of the piston, and a check valve in said outlet.

JOSEPH W. JONES.
